US00D996360S

(12) **United States Design Patent** (10) **Patent No.:** **US D996,360 S**
Zhang et al. (45) **Date of Patent:** **** Aug. 22, 2023**

(54) **WIRELESS CAR CHARGER**

(71) Applicant: **BEIJING XIAOMI MOBILE SOFTWARE CO., LTD.**, Beijing (CN)

(72) Inventors: **Lei Zhang**, Beijing (CN); **Fen Tang**, Beijing (CN); **Zhiyao Wang**, Beijing (CN); **Ningning Li**, Beijing (CN)

(73) Assignee: **BEIJING XIAOMI MOBILE SOFTWARE CO., LTD.**, Beijing (CN)

(**) Term: **15 Years**

(21) Appl. No.: **35/512,969**

(22) Filed: **Aug. 19, 2021**

(80) **Hague Agreement Data**

Int. Filing Date: **Aug. 19, 2021**

Int. Reg. No.: **DM/217304**

Int. Reg. Date: **Aug. 19, 2021**

Int. Reg. Pub. Date: **Nov. 19, 2021**

(30) **Foreign Application Priority Data**

Feb. 20, 2021 (CN) 202130099533.0

(51) **LOC (14) Cl.** **13-02**

(52) **U.S. Cl.**

(57) **CLAIM**

The ornamental design for a wireless car charger, as shown and described.

DESCRIPTION

1.1 is a front view of a wireless car charger showing the new design;

1.2 is a back view thereof;

1.3 is a left side view thereof;

1.4 is a right side view thereof;

1.5 is a top view thereof;

1.6 is a bottom view thereof;

1.7 is a front, left perspective view thereof;

1.8 is a back, right perspective view thereof;

1.9 is a partially enlarged view of reproduction 1.5; and

1.10 is a partially enlarged view of reproduction 1.6.

The broken lines depict portions of the wireless car charger that form no part of the claimed design.

1 Claim, 9 Drawing Sheets
